UNITED STATES PATENT OFFICE.

CHARLES P. KLOMER, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

SHEET-REGISTERING DEVICE.

1,419,149.

Specification of Letters Patent. Patented June 13, 1922.

Application filed February 2, 1920. Serial No. 355,549.

To all whom it may concern:

Be it known that I, CHARLES P. KLOMER, a citizen of the United States, residing at Pittsburgh, in the county of Allegheny and 5 State of Pennsylvania, have invented new and useful Improvements in Sheet-Registering Devices, of which the following is a specification.

My invention relates to automatic devices 10 for bringing sheets into register upon a supporting surface prior to a printing or kindred operation.

In printing, it is usual to provide the platen or other sheet-supporting surface 15 with one or more end stops against which the end of the sheet abuts and with one or more side stops against which a side of the sheet abuts. When the sheet engages against both the end and the side stops it is in correct 20 register. Automatic devices have been heretofore provided for bringing the sheets into such engagement with the end and side stops. It is an object of my invention to improve generally upon devices of this character. 25 It is another object of my invention to provide a register device in which means are provided for definitely retaining the sheet-engaging member against movement at the time when it is receiving a sheet. Another 30 object of my invention lies in the provision of a register device which will move the sheets with especial smoothness and ease and without marring the sheet-supporting surface. It is still a further object of my invention 35 to provide a sheet registering device capable of giving good registering results when used in connection with sheets varying within wide limits of size. Other objects will appear from the following specification and claims.

As an example, I have described in the following specification, and shown in the accompanying drawings, one embodiment of my invention as applied to the platen of a 45 job press. I wish it to be understood, however, that the invention may be embodied in other forms, and that changes may be made in the form described and shown, without exceeding the scope thereof, as defined in the 50 appended claims.

In the drawings:

Fig. 1 is a plan of the platen of a job press, having a sheet register device constructed

in accordance with my invention applied thereto:

Fig. 2 is an enlarged plan of the register device removed from the platen;

Fig. 3 is an elevation of the same;

Fig. 4 is a section on the line 4—4 of Fig. 2, looking in the direction of the arrows, the 60 platen grippers being in their raised position;

Fig. 5 is a section on the line 5—5 of Fig. 2, looking in the direction of the arrows, the 65 platen grippers being in their closed position;

Fig. 6 is a view showing the action of the register arm when a small sheet is to be registered; and

Fig. 7 is a similar view showing the action 70 of the register arm when a large sheet is to be registered.

The register device is herein described as applied to the platen of a Gordon press. Such a press comprises a platen 10, mounted 75 so as to be capable of being rocked into and out of operative relation with the type-bed of the press, having bails 11 for securing a tympan 12 thereon. A gripper bar 13 is mounted to rock in bearings carried by the 80 platen and has grippers 14 connected therewith so as to be longitudinally adjustable thereof. When the platen is near its printing position, the grippers 14 press downwardly upon the sheet to be printed, the top 85 of the gripper bar 13 being then substantially parallel with the surface of the tympan. When, however, the platen is in position for receiving the sheet, the grippers 14 are raised therefrom as indicated in 90 dotted lines in Fig. 4, the gripper bar being then rocked to a position in which its top is at an angle to the surface of the platen. To permit my improved register device to be applied, the gripper bar 13 has a portion of 95 its lower front edge cut away, as at 15.

My improved register device comprises a base 16 having holes therein for the passage of studs 17. These studs pass upwardly through the platen and are threaded therein, 100 being provided with screw-driver slots 18 to permit vertical adjustment of the device. The base 16 engages against collars 19 on the studs and is secured in such engagement by nuts 20.

Extending upwardly from the base 16 is

a standard 21, located so that its front edge engages closely against the edge of the platen, having a hole 22 extending therethrough and restricted near the top to form 5 a shoulder 23. Passing through the hole 22 is a stem 24 having secured to the lower end thereof a gear wheel 25. Upon the stem 24 is mounted a sleeve 26 the end of which enters the hole 22 and is engaged by one end of 10 a compression spring 27, the opposite end of such spring engaging the shoulder 23. At its upper end, the stem 24 is formed with a cylindrical head 27^a having a pin 28 forced therethrough in such a manner that one- 15 half of the pin is located beneath the face of the head on one side of the latter, the pin being cut away on the opposite side. The top of the standard 21 is formed with a collar 29 which is cam-shaped on its upper 20 surface, such surface sloping downward from the front to the rear and being formed at the center of the front with a depression 30 in which the projecting portion of the pin 28 normally lies, being held in such engagement by the spring 27.

A to and fro rotating movement is imparted to the gear wheel 25 by means of an arcuate rack 31 which is maintained in operative relation with the gear wheel by 30 being passed through a guide groove 32 formed in a post 33 which extends downward from the base 16. The rack 31 is pivoted to a bracket 34 consisting of an upper and lower clamping member, which 35 members embrace the rear side of the gripper bar 13 between them. It will be noted that as the gripper bar 13 rocks from the position shown in dotted lines in Fig. 4 to that shown in Fig. 5, the gear 25 and consequently the head 27^a will be rotated in a 40 clockwise direction, a contrary movement taking place when the gripper bar returns to its former position.

Extending upward from the base 16 is a 45 post 35 carrying at its top end a screw 36 which passes through a slot 37 in an arm 38 extending from a plate 39. The plate 39 is pivotally connected with the head 27^a by means of a screw 40 disposed eccentric to 50 the latter, and has secured thereto a leaf spring 41 having a slot 42 therein, said spring engaging against the under surface of the head of the screw 36. The leaf spring 41 operates to maintain the plate 39 against looseness or rocking on the head 27^a.

At its end remote from the screw 36, the 55 plate 39 is bent over to form a socket 43 for receiving the shank 44 of a sheet receiving register fork 45.

60 The operation of the device is as follows: When a sheet, 46, is fed to the platen it will assume a position such as indicated in Fig. 1, engaging with its edge in the register fork 45. The grippers 14 are then raised, 65 as indicated in Fig. 4. As the platen swings

toward printing position, the gripper bar 13 begins to swing upward, thus, by means of the rack 31, causing the gear 25 and head 27^a to rotate. The first effect of the rotation of the head 27^a is to cause the pin 28 to ride 70 up out of the depression 30, thereby raising the plate 39, register fork 45 and the sheet 46 engaged in the latter through a small distance. As the rotation of the head 27^a continues, the register fork is caused to describe 75 a curve downward and to the left, thereby bringing the sheet against the end register stops 47 and side register stop 48. The downward slope of the top surface of the collar 29 causes the register fork to be gradually lowered as it carries the sheet towards the stops. When the platen returns to sheet-receiving position, the head 27^a and register fork are brought back to the position indicated in Figs. 1-3, ready for another sheet. 80

The register device described above has several important advantages. One of these is that by the engagement of the pin 28 in the depression 30 of the register fork is held rigid, in spite of any looseness or play 90 which might exist in the parts, during the time that it is receiving a sheet. This is a considerable benefit, particularly when the device is being used with an automatic feeding mechanism, which would place the sheets 95 on the platen with some speed and force. Another advantage lies in the ease and smoothness of the moving of the sheet which is obtained by slightly raising it off the tympan at the beginning of the registering movement. Another advantage lies in the fact that the register fork clears the paper after a relatively small lateral movement. The importance of this will readily be apparent from Fig. 6, which illustrates the 100 use of the device in registering a small sheet. To register such a sheet the register fork will ordinarily need to have a long shank; yet it must clear the paper in a sufficiently small space to leave room for the register 110 stop 47 at the lower left-hand side of the sheet. Thus the smallness of the lateral movement of the register fork of my improved device enables sheets of smaller size to be registered thereby than would otherwise be convenient. Whilst the register fork has a relatively small lateral movement when a long shank is being used, it still has sufficient movement properly to register a 115 large sheet when a short shank is being used, as will be apparent from Fig. 7.

Having thus fully described my invention, what I claim as new and desire to secure by Letters Patent, is:

1. A sheet registering device comprising a 125 sheet-engaging member and means for operating said member, said operating means including a bearing member for attachment to a platen, a stem mounted in said bearing member, a gear carried by said stem, and 130

a rack for attachment to the gripper bar of said platen, said rack operating with said gear.

2. A sheet registering device comprising
5 a sheet-engaging member and means for operating said member, said operating means including a bearing member for attachment to a platen, a stem mounted in said bearing member, and means for attachment to the
10 gripper bar of said platen to cooperate with said stem.

3. A sheet registering device comprising a sheet-engaging member and means for operating said member, said operating means including a bearing for attachment to a platen, a stem rockably mounted in said bearing member, an arcuate driving member for attachment to the gripper bar of said platen, said driving member cooperating with said
20 stem.

4. A sheet registering device comprising a sheet-engaging member and means for operating said sheet-engaging member, said operating means including a gear and a rack
25 for attachment to the gripper bar of a platen, said rack engaging said gear.

5. A sheet registering device comprising a sheet-engaging member and means for operating said sheet engaging member, said operating means including a rack for attachment to the gripper bar of a platen, a support for attachment to said platen, and a gear mounted to rock with respect to said support and cooperating with said rack.
30

35 6. A sheet registering device comprising a sheet-engaging member, and means for operating said sheet engaging member, said operating means including a rack for attachment to the gripper bar of a platen, a support for attachment to said platen, and a gear for cooperation with said rack, mounted to rock with respect to said second named support, said second named support having means for guiding said rack to maintain it in operative position with respect to said gear.
40

45 7. A sheet registering device comprising a sheet-engaging member and means for operating said sheet engaging member, said operating means including a support for attachment to the gripper bar of a platen, a rack pivotally connected with said support, a support for attachment to said platen, and a gear, for cooperation with said rack, mounted to rock with respect to said support.
50

55 8. A sheet registering device comprising a sheet-engaging member and means for operating said sheet engaging member, said operating means including a support for attachment to the gripper bar of a platen, a rack pivoted to said support, a support for attachment to said platen, and a gear, for cooperation with said rack, mounted to rock with respect to said second named support,
60

said second named support having means for guiding said rack to maintain it in an operative position with respect to said gear.

9. A sheet registering device comprising a base, a member longitudinally movable and rockable with respect to said base, said base and member having cooperating surfaces formed to cause a longitudinal movement of said member when same is rocked with respect to said base, and a sheet-receiving member cooperating with said first-named member.
70

10. A sheet registering device comprising a base, a stem mounted in said base and longitudinally movable and rockable with respect thereto, a head carried by said stem, said head and base having cooperating surfaces for causing longitudinal movement of said stem when the latter is rocked with respect to said base, and a sheet-receiving member cooperatively associated with said head.
80

11. A sheet registering device comprising a base, a head longitudinally movable and rockable with respect to said base, said head and base being formed with cooperating surfaces for causing longitudinal movement of said head when the latter is rocked with respect to said base, resilient means for maintaining said surfaces in cooperative relation, and a sheet engaging member cooperatively associated with said head.
90

12. A sheet registering device comprising a base, a stem longitudinally movable and rockable in said base, a head carried by said stem, a spring tending to maintain said head in engagement with said base, said base and head being formed with cooperating surfaces for effecting a longitudinal movement of said stem when the latter is rocked with respect to said base, and a sheet-engaging means cooperatively associated with said head.
100

13. A sheet registering device comprising a base for attachment to a platen, a member longitudinally movable and rockable with respect to said base, said member and base being formed with cooperating means for effecting a longitudinal movement of said member when the latter is rocked with respect to said base, a driving member for attachment to the gripper bar of said platen cooperating with said member to rock the latter and a sheet engaging member cooperatively associated with said first named member.
110

14. A sheet registering device comprising a base for attachment to a platen, a member longitudinally movable and rockable with respect to said base, said member and said base having cooperating means for effecting longitudinal movement of said member when the latter is rocked with respect to said base, a gear carried by said member, a rack for attachment to the gripper bar of said
120
125
130

platen cooperating with said gear and a sheet engaging member cooperatively associated with said first-named member.

15. A sheet registering device comprising 5 a base for attachment to a platen, a longitudinally movable stem rockably mounted in said base, a head on said stem, said head and said base having cooperating means for effecting longitudinal movement of said stem 10 when the latter is rocked, a gear carried by said stem, a rack for pivotal attachment to the gripper bar of said platen, and a sheet engaging member cooperatively associated with said head.
- 15 16. A sheet registering device comprising a registering member having sheet engaging means associated therewith, means for moving said member to effect register of a sheet, and means for impositively locking said 20 member against movement when in one of its positions.

17. A sheet register device comprising a registering member having sheet engaging means associated therewith, means for moving said member from an initial position to a position wherein the sheet has been registered, and means for impositively locking said member against movement when in its said initial position.

30 18. A sheet registering device comprising a base, a member mounted to rock with respect to said base and having sheet engaging means associated therewith, said member and said base having cooperating means for 35 impositively locking said member against movement when in one of its positions, and means for rocking said member with respect to said base.

19. A sheet registering device comprising 40 a base, a member longitudinally movable and rockable with respect to said base, said member having sheet engaging means cooperatively associated therewith, said member and said base having cooperating means for effecting a longitudinal movement of said member when the latter is rocked with respect to said base and for impositively locking said member against movement when in one of its positions, and means for rocking 45 said member with respect to said base.

20. A sheet registering device comprising a crank member rockable substantially in the plane of the sheet, a sheet engaging device cooperating with said crank member and 55 guiding means cooperating with said sheet engaging device.

21. A sheet registering device comprising a crank member rockable substantially in the plane of the sheet, a member cooperatively 60 associated with said crank member, and having a socket, a sheet engaging member in said socket and guiding means cooperating with said second named member.

22. A sheet registering device comprising 65 a crank member rockable substantially in the

plane of the sheet, a registering member cooperatively associated with said crank member, sheet engaging means associated with said registering member and guiding means cooperating with said registering member.

23. A sheet registering device comprising 70 a crank member rockable substantially in the plane of the sheet, a registering member cooperatively associated with said crank member having an extension, sheet engaging 75 means associated with said registering member and guiding means cooperating with said extension.

24. A sheet registering device comprising 80 a crank member rockable substantially in the plane of the sheet, a registering member connected with said crank member, said registering device having a socket and extension, a sheet engaging member in said socket, and guiding means cooperating with said extension.

25. A sheet registering device comprising 85 a base, a member connected with said base to rock substantially in the plane of the sheet, means for rocking said member, a register member connected with said first named member eccentrically thereof and having sheet engaging means associated therewith, and guiding means cooperating with said register member.

26. A sheet registering device comprising 90 a base, a member mounted to rock with respect to said base, means for rocking said member, means for impositively locking said member against movement when in one of its positions, a register member connected with said first named member eccentrically thereof and having sheet engaging means associated therewith, and guiding means cooperating with said register member.

27. A sheet registering device comprising 100 a base for attachment to a platen, a member mounted to rock with respect to said base, driving means for attachment to the gripper bar of said platen and cooperating with said member to rock the same, a sheet register connected with said first named member eccentrically thereof, and guiding means operating with said sheet register member.

28. A sheet registering device comprising 110 a base for attachment to a platen, a member mounted to rock with respect to said base, a gear carried by said member, a rack for attachment to the gripper bar of said platen, cooperating with said gear, a register member connected with said first named member eccentrically thereof, and guiding means operating with said register member.

29. A sheet registering device comprising 120 a base for attachment to a platen, a stem longitudinally movable and rockable with respect to said base, a head on said stem, said head and said base having cooperating means for effecting a longitudinal movement of said stem when the latter is rocked with 130

respect to said base, a gear carried by said stem, a rack for pivotal attachment to the gripper bar of said platen, cooperating with said gear, a register member connected with 5 said head eccentrically thereof, and guiding means cooperating with said register member.

30. A paper registering device comprising a platen adapted to receive paper, a plurality of paper stops thereon, an arm adapted 10 to grip the paper and mounted in association

with said platen, a gearing unit connected with said arm, a rocker bar adapted to be actuated periodically, and means connecting said gearing unit with said rocker bar where- 15 by the gearing unit is moved to actuate the paper-gripping arm.
